US00D671333S

(12) **United States Design Patent**
Metcalf et al.

(10) **Patent No.:** **US D671,333 S**
(45) **Date of Patent:** **** Nov. 27, 2012**

(54) **LOUNGE CORNER UNIT**

(75) Inventors: **Keith E. Metcalf**, Jasper, IN (US);
Ralph L. Langen, Santa Claus, IN (US);
Jeffrey P. Bueltel, Huntingburg, IN (US);
Todd E. Boyd, Jasper, IN (US);
Stanley J. Epple, Jasper, IN (US)

(73) Assignee: **Kimball International, Inc.**, Jasper, IN (US)

(**) Term: **14 Years**

(21) Appl. No.: **29/408,767**

(22) Filed: **Dec. 16, 2011**

(51) LOC (9) Cl. **06-01**

(52) U.S. Cl. **D6/378**

(58) Field of Classification Search D6/334-336,
D6/364, 371-373, 374, 375, 377, 378, 381,
D6/500-502; 297/232, 233, 448.2, 451.8,
